CLAIM

The ornamental design for a reagent plate, as shown and described.

DESCRIPTION

FIG. 1 is a front perspective view of a reagent plate showing of our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are included for the purpose of illustrating portions of the reagent plate that form no part of the claimed design.

1 Claim, 3 Drawing Sheets
